KEEPER MECHANISM

Daniel R. Shirley, De Quincy, La.

Application April 20, 1948, Serial No. 22,121

3 Claims. (Cl. 292—341.17)

1

This invention relates to gates, and more particularly to gate latching structure.

A main object of the invention is to provide a novel and improved gate device which is very simple in construction, easy to manipulate by adults but not opened readily by children or animals, and which is useful as a farm gate, yard gate, or at any other location where a latched gate is desirable.

A further object of the invention is to provide an improved gate latch structure which involves only a few parts, is very durable, and which permits the gate to be swung on either side of the latching post so that it may be opened either inwardly or outwardly with respect to the enclosure with which it is employed.

Further objects and advantages of the invention will become apparent from the following description and claims, and from the accompanying drawings, wherein:

Figure 1 is a front elevational view, partly in cross-section, of an improved gate constructed in accordance with the present invention.

Figure 2 is a top plan view of the gate structure of Figure 1.

Figure 3 is a vertical cross-sectional view taken on line 3—3 of Figure 2.

Figure 4 is a cross-sectional detail view taken on line 4—4 of Figure 1.

Figure 5 is a fragmentary side elevational view of the top portion of the gate structure of Figure 1 showing the top cross bar in open position.

Figure 6 is a cross-sectional detail view similar to Figure 4 but illustrating a modification of the latch structure of the present invention.

Referring to the drawings, 11 designates the main body of the gate, said body having a plurality of vertical bars 12 which are secured to top and bottom horizontal bars 13 and 14. Secured to the ends of bars 13 and 14 is a vertical bar 15 provided with upper and lower screw eyes 16 and 16'. Designated at 17 is a vertical post having a sharpened lower end 18, whereby post 17 may be driven into the ground. Post 17 is provided with vertically aligned L-shaped hinge screws 19 and 20 on which the respective screw eyes 16 and 16' are engaged, pivotally supporting the gate 11 for swinging movement around the vertical axis defined by the hinge screws 19 and 20.

Designated at 21 is a vertical post member having a sharpened lower end 22. Post member 21 is driven into the ground adjacent the free end of gate body 11. Rotatably secured to the intermediate portion of post member 21 are re-

2

spective star-shaped cam members 23 and 24 located in the same horizontal plane and spaced symmetrically with respect to the vertical plane of the gate. Secured to post member 21 below the plane of cam members 23 and 24 is a triangular lug 25 whose apex is directed upwardly and is located in the vertical plane of the gate equidistant from the rotatable star-shaped cam members 23 and 24. In the specific embodiment illustrated herein, each cam member has four equally spaced radial arms 26.

Pivots connected at 27 to one of the intermediate vertical bars 12 is a latch bar 28 which extends through a vertical slot 29 in the end vertical bar 12 and is provided with a cylindrical head 30 at its free end. As shown in Figure 4, head 30 is engageable between the star cams 23 and 24. A coiled spring 31 connects the intermediate portion of latch bar 28 to the upper horizontal bar 13 of gate body 11 and biases latch bar 28 to the position shown in Figures 1 and 4, whereby the gate body 11 is held against inward or outward swinging movement. Pivots connected at 32 to latch bar 28 is a vertical rod 33 which passes slidably through a vertical slot 34 in upper horizontal bar 13 and is provided at its top end with a push knob 35. By pushing downwardly on knob 35, latch bar 28 may be rotated clockwise, as viewed in Figure 1. The axis of head 30 is normally in the same horizontal plane as the axes of cams 23 and 24. When latch bar 28 rotates downwardly, the axis of head 30 moves below said horizontal plane, and the gate may then be swung either inwardly or outwardly.

Downward movement of head 30 is limited by the apex of lug 25. When head 30 engages said apex, only a small amount of force is required to swing the gate since the cams 23 and 24 will then be freely rotatable to allow the head 30 to disengage itself from one of the other of said cams.

To close the gate, push button 35 is depressed sufficiently to lower head 30 from a dead center relation with either the cam 23 or 24 when it engages the cam. As the gate is swung closed, head 30 rotates the cam it engages and is moved thereby into locking position above the apex of triangular lug 25, said lug cooperating with head 30 to guide it into locking position between the cams 23 and 24. As head 30 reaches a position above lug 25, spring 31 rotates latch bar 28 upwardly, causing head 30 to rise to dead center position between the cams 23 and 24, illustrated in Figure 4.

In the modification illustrated in Figure 6, the post member 21 is provided with merely a single

rotary star cam 36 and secured on said post member below cam 36 is a bar element 37 formed with a V-notch 38 vertically aligned with the axis of cam 36. When the gate is in a locked position, head 30 is engaged between the lower radial arms of cam 36 and is seated in the V-notch 38. The gate may be opened by exerting sufficient horizontal force thereon to cause head 30 to rotate cam 36. As the gate is swung, spring 31 assists head 30 in rotating cam 36, whereby said head may disengage itself from the V-notch 38. In closing the gate, head 30 is moved against the cam 36, forcing the cam to rotate and to move the head into the V-notch 38. Here again, push knob 35 may be depressed slightly to lower head 30 from a dead center relation to cam 36 as it begins its locking movement.

Secured to the top end of post member 17 are a pair of short horizontal parallel bars 39, 39 formed adjacent their inner ends with aligned transverse grooves 40, 40. Secured to the top end of post member 21 are similar inwardly extending parallel horizontal bars 41, 41. Secured transversely to bars 39, 39 inwardly of grooves 40, 40 is a pin member 42. Designated at 43 is a cross bar formed with an inwardly tapering slot 44 through which pin 42 passes, the cross bar 43 being thereby movably secured between the respective parallel bars 39, 39 and 41, 41. Secured transversely to cross-bar 43 is a short locking bar 45 which is engageable in the grooves 40, 40 to lock cross bar 43 against endwise movement when it is in the position shown in Figures 1 and 2. As shown in Figure 3, cross bar 43 is formed with shallow notches 46 and 47 respectively receiving the top ends of post members 17 and 21. In this position pin 42 is in the upper left hand corner of slot 44, as shown in full line view in Figure 3. By lifting cross bar 43 slightly, bar 45 may be disengaged from grooves 40, 40 and recesses 46 and 47 may be disengaged from the top ends of post members 17 and 21. Cross bar 43 may then be moved endwise to the left as shown in dotted view in Figure 3 to a position wherein the free end of the cross bar clears post member 21. The cross bar may then be allowed to drop to a vertical position, as shown in Figure 5, allowing relatively high loads to pass through the gate. By reversing the above described procedure, the cross bar 43 may be returned to its horizontal locked position.

While certain specific embodiments of a gate latching structure have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A keeper mechanism comprising a vertically disposed star shaped cam mounted on an up-

standing gate post intermediate its upper and lower ends for rotary movement about a horizontal axis, and a vertically disposed projection fixedly secured to said gate post positioned below and spaced from said cam for receiving therebetween a free end of a vertically movable latch bar, said cam being adapted to engage the free end of said latch bar and being rotated responsive to the vertical movement of said latch bar relative to said projection.

2. A keeper mechanism comprising a vertically disposed star shaped cam mounted on an up-standing gate post intermediate its upper and lower ends for rotary movement about a horizontal axis, and a vertically disposed bar element fixedly secured to said gate post positioned below and spaced from said cam for receiving the free end of a vertically movable latch bar, said cam being adapted to engage the free end of said latch bar and being rotated responsive to the vertical movement of said latch bar relative to said bar element, there being a V-shaped notch in the upper edge of said bar element for seatingly receiving the free end of said latch bar when the latter has executed its vertical movement relative to said bar element.

3. A keeper mechanism comprising a pair of star shaped cams arranged in spaced relation and in the same vertical plane positioned adjacent to a gate post intermediate its upper and lower ends, each cam being mounted on said gate post for rotary movement about a horizontal axis, and a vertically disposed triangular lug having its apex contiguous to and substantially centrally between said pair of cams fixedly secured to said gate post positioned below and spaced from said cams for receiving therebetween the free end of a vertically movable latch bar, said pair of cams being adapted to engage therebetween the free end of said latch bar and being rotated responsive to the vertical movement of said latch bar relative to said lug.

D. R. SHIRLEY.
